CLAIM

The ornamental design for a paper sheet dispenser, as shown and described.

DESCRIPTION

FIG. 1 is a top perspective view of a paper sheet dispenser according to our new design;

FIG. 2 is a bottom perspective view of the paper sheet dispenser FIG. 1;

FIG. 3 is a front view of the paper sheet dispenser FIG. 1; FIG. 4 is a first side view of the paper sheet dispenser FIG. 1;

FIG. 5 is a second side view of the paper sheet dispenser FIG. 1;

FIG. 6 is a back view of the paper sheet dispenser FIG. 1;

FIG. 7 is a top view of the paper sheet dispenser FIG. 1; and, FIG. 8 is a bottom view of the paper sheet dispenser FIG. 1.

The broken lines of FIGS. 1-8 depict portions of the paper sheet dispenser forms no part of the claimed design. The stippled area is a portion of the paper sheet dispenser having a first color and the lined area is a portion of the paper sheet dispenser having a second color different from, and in contrast with, the first color.

1 Claim, 6 Drawing Sheets
